Attorney

UNITED STATES PATENT OFFICE

FERD G. DIESCH, OF HAYFIELD, MINNESOTA

CANVAS HOLDER

Application filed May 6, 1930. Serial No. 450,272.

This invention appertains to combination harvesters and threshers and like machines, and more particularly to an attachment therefor.

One of the primary objects of my invention is to provide novel means for holding and handling the canvas of the platform of combination harvesters and threshers, said means embodying supporting members for resting on the harvester platform and the ground, the members carrying supporting devices for the canvas whereby the same can be conveniently pulled from off of its roll onto the platform.

A further object of my invention is the provision of a novel canvas handling device for the platforms of combined harvesters and threshers and windrowers embodying a pair of companion members having the upper ends thereof hooked for connection with the platform and supporting pins against which the roll of canvas is adapted to engage, each of the members carrying side guards for preventing the roll of canvas from slipping off of the supporting pins.

A still further object of my invention is to provide a novel means for handling canvas of a combined harvester and thresher platform of the above character, which will be durable and efficient in use, one that will be simple and easy to manufacture, and one which can be placed upon the market at a reasonable cost.

With these and other objects in view, the invention consists in the novel construction, arrangement and formation of parts, as will be hereinafter more specifically described, claimed, and illustrated in the accompanying drawings, in which drawings:

Figure 1 is a front elevation of my improved canvas holder showing the same associated with the platform of a combined harvester and thresher.

Figure 2 is a section taken on the line 2—2 of Figure 1 looking in the direction of the arrows.

Figure 3 is a detail horizontal section taken on the line 3—3 of Figure 2 looking in the direction of the arrows, and

Figure 4 is a detail perspective view of one of the side members.

Referring to the drawings in detail, wherein similar reference characters designate corresponding parts throughout the several views, the letter A generally indicates my improved device for handling a roll of canvas R for the platform P of a combined harvester and thresher or similar machine.

My improved device A embodies a pair of like companion members or supports 10 and 11, the same being similar in all respects with the exception that one is made left-handed and the other right-handed, as will become apparent as the description proceeds.

Each of the members 10 and 11 include a pair of spaced supporting metal rails or plates 12 connected together by metal straps 13. The upper ends of the rails 12 are provided with hooks 14 for engaging over the edge of the platform P. The inner rail of each member is provided with an outstanding pin 15 and the outer rail of each of the members is provided with a metal guard 16. The metal guard 16 is bolted or otherwise secured to the outer face of the outer rail 12 of each of the members 10 and 11 adjacent to the pin 15.

In use of my improved canvas holder the members 10 and 11 are placed with the upper ends 14 thereof over one edge of the platform and the lower ends of the members 10 and 11 are placed upon the ground. The roll of canvas R is now placed on the pins or arms 15 with the ends thereof engaging the guards 16. The canvas can now be readily pulled off of the roll onto the platform, the pins 15 forming an effective support for the roll while the guards 16 prevent the roll from slipping off of the pins and likewise from uneven unwinding. Due to the fact that the members 10 and 11 are made independent of one another, the same can be readily adjusted as to position when in use, that is, the members can be moved toward and away from one another according to the width of the roll of canvas being used and the width of the platform.

From the foregoing description, it can be seen that I have provided a novel device for handling a roll of canvas of the platforms of combined threshers and harvesters.

Changes in details may be made without departing from the spirit or the scope of this invention, but :—

What I claim as new is:

- 5 1. A device for facilitating the handling of canvas for the platforms of combined harvesters and threshers and like machines comprising a pair of like members each of which are independent of the other, hooks formed on
- 10 the upper ends of the members for engaging the platforms, outstanding arms carried by said members intermediate the ends thereof for supporting a roll of canvas, and guards carried by the outer sides of said members
- 15 for engaging the ends of the roll of canvas.
2. A device for handling canvas for the platforms of combined harvesters and threshers and like mechanism comprising a pair of like members, each of which embodies a pair
- 20 of side rails, connecting rungs for the rails, hooks formed on the upper ends of the rails, for engaging the platform of the combined harvester and thresher, an outstanding pin carried by the inner rail of each member, and
- 25 a flat sheet metal guard secured to the outer rail of each member adjacent to the pin.

In testimony whereof I affix my signature.

FERD G. DIESCH.
